UNITED STATES PATENT OFFICE.

GEORGE H. BUZZELL, OF BOSTON, MASSACHUSETTS, ASSIGNOR OF ONE-HALF
TO FRANK O. BUZZELL, OF BANGOR, MAINE.

PIPE-WRENCH.

SPECIFICATION forming part of Letters Patent No. 463,784, dated November 24, 1891.

Application filed March 20, 1891. Serial No. 385,754. (No model.)

To all whom it may concern:

Be it known that I, GEORGE H. BUZZELL, of Boston, in the county of Suffolk, State of Massachusetts, have invented certain new and useful Improvements in Pipe-Wrenches, of which the following is a description sufficiently full, clear, and exact to enable any person skilled in the art or science to which said invention appertains to make and use the same, reference being had to the accompanying drawings, forming part of this specification, in which—

Figure 1 is a side elevation of my improved pipe-wrench; Fig. 2, an edge elevation of the same; and Fig. 3, a side elevation of the jaws represented as in use, the handle and a portion of one of the straps being represented as broken away.

Like letters of reference indicate corresponding parts in the different figures of the drawings.

My invention relates especially to that class of wrenches known as "pipe-wrenches;" and it consists in certain novel features herein-25 after fully set forth and claimed, the object being to produce a simpler, cheaper, and more effective device of this character than is now in ordinary use.

The nature and operation of the improvement will be readily understood by all conversant with such matters from the following explanation.

In the drawings, A represents the body of the wrench, and B the handle; C, the fixed jaw, and D the movable jaw. The body A comprises a flattened bar screw-threaded at b on opposite faces, and secured by ordinary means in the wooden handle B. The fixed jaw C has a serrated head d and a shank f, 35 which is pivoted at g to the body A to swing in one direction or from left to right, as viewed in Fig. 1. A rosette or nut h is mounted to travel on the body A, and carries with it a strap i, encircling said body and inclosing 40 said nut. The movable jaw D is pivoted to swing vertically in said strap at j, and has a serrated head k. A strap m is pivoted to the head k of the movable jaw and encircles the shank f of the fixed jaw, said strap being fitted 45 to slide freely on said shank and of suitable 50 length to permit the swinging of the shank

therein. Below the pivot j the movable jaw is extended slightly downward or provided with a projection p, which is adapted to engage a jam-nut h when the head k of said jaw is thrown outward.

In the use of my improvement the wrench-jaws are adjusted by means of the nut h, in the usual manner, until their heads d k, respectively, engage the pipe H. By moving 60 the handle B downward or from left to right, as viewed in Fig. 1, the pivot g is caused to swing outward, inclining the shank f, as shown in Fig. 3, and causing the jaws to bite tightly against the pipe. By reciprocating the handle the jaw C again assumes an upright position, as shown in Fig. 1, enabling a new hold to be quickly obtained. The swing of the jaw D in clamping said jaws on the pipe causes its projection p to jam against the nut h, preventing said nut from accidentally traveling on the screw and obviating the necessity of constant readjustment of the jaws.

By pivoting the movable jaw and fixed jaw to swing in different arcs from the body A, as 75 shown, a greater leverage is attained than when said fixed jaw is formed integral with the handle, as in wrenches of this class of ordinary construction, the bite of the jaws on the pipe increasing proportionately to the 80 amount of power exerted on the handle.

The projection p may be omitted from the jaw D and the strap m employed to hold said jaw in position, if desired, or said strap may be omitted, the jaw being prevented from falling too far outward by the engagement of said projection p with the nut h.

Having thus explained my invention, what I claim is—

1. In a pipe-wrench, a threaded body and 90 rosette, in combination with a jaw pivoted to said body and a pivoted jaw fitted to travel on said body, substantially as described.
2. In a pipe-wrench, the combination of a body with a jaw pivoted thereon and a jaw 95 pivoted in a support fitted to slide on said body, substantially as described.
3. In a pipe-wrench, a threaded body, a nut fitted to travel thereon, and a sleeve or strap carried by said nut, in combination with a 100 jaw pivoted to said body, and a jaw pivoted in said strap, substantially as described.

4. In a pipe-wrench, the body and nut, in combination with a pivoted movable jaw having a fulcrum-support fitted to travel on said body, a jaw provided with a shank pivoted to said body, and a strap on said movable jaw encircling said shank, substantially as specified.
5. In a pipe-wrench, the body A and nut, in combination with the jaw C, pivoted to

said body, and the jaw D, pivoted in the strap *i*, to fitted to slide on said body, and provided with the projection *p* in position to engage said nut, substantially as and for the purpose set forth.

GEORGE H. BUZZELL.
